DIRECT-COUPLED AMPLIFIER WITH
DIRECT-CURRENT FEEDBACK

Russell J. Grambsch, Marshfield, Wis.

Application August 20, 1945, Serial No. 611,659

1 Claim. (Cl. 179—171)

1

The present invention relates to electronic amplifiers, and it relates more particularly to a multi-stage direct coupled electronic amplifier having an inverse feedback characteristic.

It is often necessary to have high gain amplifiers which are adapted to pass pulse-type signals of electrical energy. Due to the character of the pulses, it is necessary, in order to maintain signal fidelity, that such an amplifier have a wide band pass characteristic. Amplifiers having such a characteristic are often referred to as video amplifiers, and if a high gain is desired, they usually have a plurality of amplifying stages.

It is generally desirable that video amplifiers be responsive to both large amplitude and small amplitude pulse-type signals. In present multi-stage video amplifiers, difficulty is encountered in amplifying both large amplitude and small amplitude positive pulses, and to still provide an output having a waveform similar to the original input signal. Most of the difficulty encountered in present video amplifiers is due to large amplitude pulses overloading the amplifiers, thereby causing grid current to charge the coupling condensers used between stages of the amplifier.

It is to be understood that a positive pulse as mentioned above and as hereinafter referred to is a pulse having a positive going leading edge and a negative going lagging edge. Similarly, a negative pulse is one having a negative going leading edge and a positive going lagging edge.

It is an object of the present invention to provide a multi-stage video amplifier whose output waveform is of substantially the same shape as the waveform of the input signal.

It is another object of the present invention to provide a video amplifier which cannot be overloaded by large amplitude signals.

It is yet a further object of the present invention to provide a reliable multi-stage, direct coupled video amplifier which is substantially non-critical with respect to circuit components.

The invention, however, will be more fully understood from the following description, when taken in connection with the accompanying drawings wherein:

Fig. 1 shows a simplified schematic diagram of a conventional condenser coupled amplifier; and

Fig. 2 shows voltage waveforms which enable a better understanding of the present invention; and

Fig. 3 shows a schematic circuit diagram of one embodiment of the present invention.

An understanding of difficulties encountered in conventional condenser coupled video amplifier

2

stages may be obtained by reference to Fig. 1. Assume that a negative pulse is applied to input terminal 2 and that a resultant amplified, but positive pulse is obtained at anode 4 of vacuum tube 6. This positive signal then passes through coupling condenser 8 and grid leak resistance 10, the signal developed across the latter being applied to control grid 12 of vacuum tube 14. If condenser 8 is relatively large, the waveform applied to control grid 12 is substantially the same as that developed at anode 4. A large amplitude signal drives vacuum tube 14 into grid current, and a low impedance charging path is provided for coupling condenser 8, the result being the side of the coupling condenser nearest control grid 12 attains a large negative charge. This charge may be sufficient to cut off vacuum tube 14. The discharge path for coupling condenser 8 is then provided through resistance 10.

As the discharge time constant is long (coupling condenser 8 is large), condenser 8 maintains its charge for an appreciable length of time and vacuum tube 14 remains cut off. It is therefore apparent that if the large amplitude signal is closely followed by a signal of low amplitude, said second signal cannot cause vacuum tube 14 to conduct and hence said second signal is not amplified and does not appear at anode 16 of vacuum tube 14.

On the other hand, if condenser 8 is made small so as to prevent this large negative charge from being held by the condenser and hence the loss of small signals, it is difficult to maintain the waveform of a pulse-type signal. The effect of smaller coupling condensers is shown in Fig. 2. In the drawing, the applied input signal is shown as Fig. 2a. The signal at control grid 12 of vacuum tube 14 is shown as Fig. 2b. It should be noted that the coupling condenser charges during the pulse causing a sag in the top of the pulse and causing a surge of voltage in the other direction after the duration of the pulse. This voltage surge in the opposite direction may for simplicity be referred to as an overshoot and such overshoots are highly objectionable.

The waveforms shown in Fig. 2 have been considered only for one coupling circuit and, in fact, in most video amplifiers, a number of amplifying stages are present and hence a number of coupling circuits. Thus, if the coupling condenser is made small, a number of overshoots will be produced, the number being proportional to the number of coupling condensers. It is therefore apparent that if a number of such stages of amplification are present, more pulses than were

originally applied appear at the output, and the signal may be distorted so much as to be of little use.

Another example of difficulties caused by these undesirable overshoots is when a series of unequal amplitude pulses are amplified and employed to actuate an associated electronic circuit. Even in such an instance where fidelity of waveform is not of paramount importance a negative overshoot is troublesome. This condition is illustrated in Fig. 2. In the drawing, Fig. 2c shows a large amplitude positive pulse closely followed by a small amplitude positive pulse. Fig. 2d shows how this small amplitude pulse may be superimposed on a large negative overshoot in the positive pulse. It is therefore evident that this results in the "loss" of the small amplitude pulse.

In view of the foregoing description, it is evident that a number of difficulties are encountered in obtaining a video amplifier of the desired characteristic. Briefly, if the coupling condensers are too large, the waveform is maintained, but small signals are blocked or lost. If the coupling condensers are small, the waveform is distorted, overshoots are introduced, so as to introduce extraneous signals and small signals superimposed on overshoots may be lost. Thus video amplifiers must be designed for specific purposes and are generally responsive only for signals of a distinctive character. The present invention overcomes these difficulties by means of a novel yet simple and reliable electronic amplifier, said amplifier consisting basically of two direct coupled stages having an inverse feedback characteristic. One particular advantage of the direct coupling used in the present invention is that the circuit is substantially non-critical with respect to circuit components such as vacuum tubes. The functioning characteristics of this circuit will now be described.

Referring now to Fig. 3, which shows one embodiment of the present invention, consider a negative pulse-type signal applied to input terminal 20. The negative signal passes through input coupling capacitor 22 and is developed across grid leak resistance 24, said grid leak resistance being connected between control grid 26, and cathode 28 of vacuum tube 30. The negative pulse thus applied to control grid 26 causes a positive pulse to be developed at anode 32 of vacuum tube 30, said anode 32 being connected through resistance 34 and resistance 36 to a suitable source of positive potential 38. The function of resistance 34 is to provide inverse feedback for vacuum tube 40 as will be more fully explained hereinafter. The positive pulse developed at anode 32 is then applied directly by means of connection 42 to control grid 44 of vacuum tube 40 to cause a negative pulse to be developed at anode 46 of vacuum tube 40.

Assume that the negative pulse applied to input terminal 20 is of sufficient magnitude to drive vacuum tube 30 to cut-off thereby developing a large amplitude positive pulse at anode 32. Although the positive pulse causes grid current (from vacuum tube 40) to flow through resistance 34 and resistance 36, there is no coupling condenser to be charged. Therefore, practically as soon as the large negative pulse is removed from input terminal 20, the circuit returns to normal and is then able to respond to a small amplitude pulse. Relatively large, undistorted negative pulses may thus be developed at anode 46

of vacuum tube 40, and they may be taken through condenser 48 to output terminal 50.

The direct coupling from anode 32 of vacuum tube 30 to control grid 44 of vacuum tube 40 causes a positive voltage (with respect to ground) on said control grid. Therefore, cathode 52 of said vacuum tube must be raised above ground to obtain proper bias for vacuum tube 40. This may be accomplished by connecting cathode 52 of vacuum tube 40 through cathode biasing resistance 54 and by-pass capacitance 56 to ground.

In order to maintain a steady bias on cathode 52 and to thus prevent degenerative feedback, which reduces the gain of the amplifier, capacitance 56 should be reasonably large. This requirement normally causes difficulty, in that large amplitude positive pulses applied to control grid 44 causes by-pass condenser 56 to charge up, the result being that a large bias is maintained on cathode 52. This may be sufficient to make vacuum tube 40 non-responsive to small amplitude pulses. This undesirable effect is counteracted in the present invention by the provision of an inverse feedback voltage applied from anode 46 of vacuum tube 40, through inverse feedback resistance 34 and connection 42 to control grid 44.

Such a pulse is amplified and inverted in phase by vacuum tube 30 and is applied as a positive signal to control grid 44 of vacuum tube 40. If this pulse causes increased anode current in vacuum tube 40, the charge on by-pass condenser 56 is likewise increased, thereby causing a corresponding increased bias voltage to be developed across cathode resistance 54. This bias voltage is maintained by condenser 56 even after the negative pulse has been removed from input terminal 20. The effect of this bias is to cause the anode current through vacuum tube 40 to decrease, thereby causing anode 46 to rise in potential. This rise is communicated through inverse feedback resistance 34 and connection 42 to control grid 44.

Thus, it can be seen that the increased potential of cathode 52 has caused the potential of control grid 44 to also rise. In other words, the potential on the control grid "follows" the cathode potential as capacitance 56 is charged. As there is then very little difference between the grid to cathode potential, vacuum tube 40 is able to respond to a small signal applied to input terminal 20 and it is apparent that the entire amplifier is responsive to both large amplitude and small amplitude pulses.

By-pass condenser 56 may be eliminated in certain instances without too great a loss in amplification. This is especially true if cathode resistance 54 is made as small as practicable such as by operating vacuum tube 30 at a low anode voltage.

Another advantage of the present invention is that due to the inverse feedback characteristic, the circuit is substantially non-critical with regards to variation in circuit components. By way of example, consider the effect of changes in the characteristics of the vacuum tubes. It is well known that the emission of vacuum tubes may change with age and it is also known that vacuum tubes of the same type often vary slightly in electrical characteristics.

Assume that the emission from cathode 28 of vacuum tube 30 should decrease thereby causing

a smaller current to flow through inverse feed-back resistance 34 and resistance 36. The effect of this decreased emissivity causes the potential of anode 32 to rise, this rise in voltage being transmitted to control grid 44 of vacuum tube 40. This rise in potential in control grid 44 causes an increased anode current to flow through anode load resistance 36 and thereby decreases the voltage at anode 46. This decrease is communicated through inverse feedback resistance 34 and connection 42 to control grid 44 thus maintaining the voltage at control grid 44 substantially constant.

In a similar manner, an increase in emissivity causes anode 32 of vacuum tube 30 to drop in potential. This drop in potential is then communicated through connection 42 to control grid 44 thereby causing the potential of anode 46 to rise. The rise in potential is transmitted through inverse feedback resistance to control grid 44 thereby maintaining the voltage of said grid substantially constant.

It is to be understood that although the above invention has been described in connection with pulse-type input signals, the amplifier is adapted to be responsive to other types of input signals. Similarly, the invention is not to be construed as being limited to a two stage amplifier but may consist of a series of cascaded stages.

While there has been here described one embodiment of the present invention, it will be manifest to those skilled in the art that various changes and modifications may be made therein without departing from the invention. It is therefore aimed in the appended claim to cover

all such changes and modifications as fall within the spirit and scope of the invention.

I claim:

5 A multi-stage video amplifier having at least a first vacuum tube and a second vacuum tube, each of said vacuum tubes having at least a cathode, an anode, and a control grid, a resistance connected between the anodes of said vacuum tubes as a load resistance for said first tube and feedback resistance for said second tube, a further load resistance for both tubes from the anode of said second tube to a source of anode current, a direct electrical connection between the anode of said first vacuum tube and the control grid of said second vacuum tube, means for 10 raising the potential of the cathode of said second vacuum tube above the potential of the cathode of said first vacuum tube, means for applying a signal to be amplified to the control grid of said first vacuum tube to provide a signal 15 at said anode of said first vacuum tube whereby said signal is applied to the control grid of said second vacuum tube by said direct-current connection and whereby an amplified output is obtained at said anode of said second vacuum tube.
